UNITED STATES PATENT OFFICE

HENRY B. MILLER, OF HONEY CREEK, WISCONSIN

SCAFFOLD BRACKET

Application filed April 3, 1929. Serial No. 352,182.

This invention relates to improvements in scaffold brackets.

It is an object of this invention to provide a scaffold bracket which may be easily attached to and removed from the wall of a frame building.

More particularly it is an object to provide a scaffold bracket in which the bracket arm and brace may be extended downwardly while the wall plate is being attached to or detached from a wall, thus considerably lessening the burden upon a workman.

It is also an object to provide for the bracket arm an adjustable retainer slidable on the arm and automatically engageable therewith to prevent planking on the arm from sliding longitudinally thereof.

A further object is to provide a wall plate with nail apertures having lips adapted to direct the nails from the apertures when the plate is moved vertically along a wall to which it is attached.

Still another object is to provide for the bracket a bolt which may be extended for engagement with a block positioned upon the opposite side of studding to which the bracket is secured.

In the drawing:

Figure 1 is an isometric view showing the bracket as it will appear when attached to a wall.

Figure 2 is a plan view showing the bracket attached to a wall.

Like parts are identified by the same reference characters throughout the several views.

The bracket comprises a wall plate 1, a bracket arm 2, braces 3, and hanger 4. The wall plate shown is composed of an angle iron, the base 5 of which is provided with inverted T-shaped slots 6 having lips 7 upon the wider portion thereof. A hole 8 is also provided through which the bolt 9 extends. The side 10 of the wall plate is provided with a hook 11 and the arm 2 is pivoted to the side at 12.

Arm 2 is provided with a pair of apertures 13 and 14 adapted to receive the end 15 of bolt 9. The end 15 may be secured in either aperture by nut 16. Loosely mounted slidably on the arm 2 is a sleeve 17 having a

pointed tongue 18 projecting toward the wall plate 1. At the outer end of the arm 2 is provided a retainer 19. Pivotedly secured at 20 adjacent the outer end of the arm is a pair of diverging braces 3 secured together at their lower end by cross piece 21. Pivotally secured adjacent the lower ends of the braces is a hanger 4 providing an eye 23 adapted to receive the hook 11.

The bracket may be attached to a wall by driving nails through the small portions of the apertures 6 in the plate 1 and by passing the bolt 9 through a block 25 as shown in Figure 2. When the plate 1 is secured to a wall, the arm 2 is extended horizontally and the hanger 4 is engaged with hook 11. The braces 3 will then engage the wall and support the arm as shown. After the bracket has thus been secured to a wall, planking will be laid upon arm 2 and will be held from sliding away from the wall by the sleeve 17 or the retainer 19. The planking will engage the hook 18 as shown in Figure 1 and tilt the sleeve, thus causing the sleeve to bind with the arm 2 and hold the planking in place.

When the bracket is removed from a wall, the bolt 9 will be removed and the hanger 4 will be detached from hook 11 to permit the braces 3 and arm 2 to extend downwardly from the plate 1. The arm 2 may then be used to move the plate 1 vertically on the nails until the lips 7 cause the former to pass through larger portions of the apertures 6. The plate will then be free and the bracket may be folded for storage.

As illustrated in Figure 2 the bolt 9 may be secured to a block 26 shown in dotted line and disposed upon the inner face of siding 27. In this case the bolt will have its end 15 disposed in aperture 13 whereas in the former case the end 15 of the bolt will be disposed in aperture 14.

It is preferred to extend the arm 2 beyond the pivot 12 sufficient to engage the end 29 with the side 10 adjacent the base 5, thereby re-enforcing the side against any warping effect that may be caused by strain on the pivot 12.

I claim:

1. A collapsible scaffold bracket compris-

100

- ing a wall plate, an arm pivotally secured thereto, a brace pivotally secured to the arm, a hanger pivotally secured to the brace, and a hook on said plate, said hanger being engageable with said hook.
- 5 2. A collapsible scaffold bracket comprising a wall plate having a series of apertures disposed in vertical relation, a hook carried by the plate, an arm pivotally secured to the plate, a brace pivotally secured to the arm, and a hanger pivotally secured to the brace and having a hook receiving aperture.
- 10 3. A collapsible scaffold bracket comprising a wall plate having a series of apertures disposed in vertical relation, the lower portion of each aperture being sufficiently large to permit the head of a nail to pass therethrough; lips extending vertically over said large portions of said apertures and adapted 15 to direct the heads of nails through said portions, a hook carried by the plate, an arm pivotally secured to the plate, a brace pivotally secured to the arm, and a hanger pivotally secured to the brace and having a hook receiving aperture.
- 20 4. A collapsible scaffold bracket comprising a wall plate having a base provided with a series of apertures disposed in vertical relation and a side normal to the base including a hook, the lower portion of each aperture being sufficiently large to permit the head of a nail to pass therethrough; lips extending vertically over said large portion of the apertures and adapted to direct the heads of nails 25 through said portions, an arm pivotally secured to said side above said hook, a brace pivotally secured to the arm, and a hanger pivotally secured to the brace and having a hook receiving aperture.
- 30 5. A collapsible scaffold bracket comprising a wall plate having a base provided with a series of apertures disposed in vertical relation and a side normal to the base including a hook, the lower portion of each aperture being sufficiently large to permit the head of a nail to pass therethrough; lips extending vertically over said large portion of the apertures and adapted to direct the heads of nails 35 through said portions, an arm pivotally secured to said side above said hook, a brace pivotally secured to the arm, and a hanger pivotally secured to the brace and having a hook receiving aperture.
- 40 6. A collapsible scaffold bracket comprising a wall plate having a base provided with a series of apertures disposed in vertical relation and a side normal to the base including a hook, the lower portion of each aperture being sufficiently large to permit the head of a nail to pass therethrough; lips extending vertically over said large portion of the apertures and adapted to direct the heads of nails 45 through said portions, an arm pivotally secured to said side above said hook, a brace pivotally secured to the arm, and a hanger pivotally secured to the brace and having a hook receiving aperture, a sleeve loosely slidable on said arm, and a tongue on said sleeve projecting toward said plate, said arm having a pair of spaced apertures and said base having a hole, and a bolt extending through said hole and having one end disposed in one of said spaced apertures.
- 50 7. A collapsible scaffold bracket comprising a wall plate having a base provided with a series of apertures disposed in vertical relation and a side normal to the base including a hook, the lower portion of each aperture being sufficiently large to permit the head of a nail to pass therethrough; lips extending vertically over said large portion of the apertures and adapted to direct the heads of nails 55 through said portions, an arm pivotally secured to said side above said hook, a brace pivotally secured to the arm, a hanger pivotally secured to the brace and having a hook receiving aperture, a sleeve loosely slidable on said arm, and a tongue on said sleeve projecting toward said plate, said arm having a pair of spaced apertures and said base having a hole, and a bolt extending through said hole and having one end disposed in one of said spaced apertures.
- 60 8. In a scaffold bracket, a wall plate having a series of nail receiving apertures comprising inverted T-shaped holes, and a lip extending vertically over the larger portion of each of said apertures, whereby the heads of nails in said apertures will be directed through the larger portion thereof when the plate is moved vertically.
